United States Patent Office.

PIERRE DU RIEUX AND EDOUARD ROETTGER, OF LILLE, FRANCE.

Letters Patent No. 80,157, dated July 21, 1868.

CYLINDRICAL FILTERING-PRESS.

The Schedule referred to in these Letters Patent and making part of the same.

TO ALL WHOM IT MAY CONCERN:

Be it known that we, PIERRE DU RIEUX and EDOUARD ROETTGER, of Lille, in the Empire of France, civil engineers, French subjects, have invented or discovered a new and useful improved Cylindrical Filtering-Press; and we, the said PIERRE DU RIEUX and EDOUARD ROETTGER, do hereby declare the nature of the said invention, and in what manner the same is to be performed, to be particularly described and ascertained in and by the following statement thereof; that is to say—

Our invention consists in an improved construction and arrangement of the parts of filtering-presses, whereby a more efficient working is obtained, and all danger of the machine exploding under pressure is avoided, and the operations of filtering the liquid parts and caking the solid parts of semi-liquids may be conducted with more speed, regularity, safety, and efficiency.

According to these improvements, the filtering-chambers are cast of a cylindrical shape, so as to present a uniform resistance to the pressure within. The said filtering-chambers or frames consist of a circular rim or ring, the central portion of which is provided with a series of bars cast with the rim, but less wide than the rim, so that when a certain number of the said rings or circular frames, with their gratings, are secured together face to face, they will form two series of chambers, the one composed of gratings, the second of hollow spaces between the said gratings, equal in width to the difference between the width of the grating and the width of their surrounding rings. On each side of the said gratings are attached perforated metal plates, and over those plates are one or more cloths or other filtering-medium, which may be secured to the ring or rim of the frame, either by means of a metallic ring taking into a groove, over which ring the cloth is tightened so as to be easily removed with the said ring, or by forming the ring of the frame so that the cloth may be secured thereto without injury by a cord or rope, which at the same time insures its contact with the surface of the metal perforated plate over the grating.

Through the upper part of each rim of the circular frames is an aperture or channel, which channels, when the circular frames are secured together face to face, communicate one with the other throughout the entire length of the machine, and also with the spaces within and between the said frames. The continuous channel formed by the said apertures communicates externally by cocks and pipes, or other similar means, with the machinery used for forcing in the semi-liquid substance to be operated upon; and we prefer that the semi-liquid substance should be forced into the apparatus by means of the direct pressure of steam acting in a "monte-jus," or juice-elevator.

The circular frames are each provided with side projections or arms, which rest upon the longitudinal bars of a supporting-frame, and the circular frames, when in position, are closed before and behind by strong metallic circular plates, the inner surfaces of which are formed with gratings, and parts similar to those of the inner circular frames, so as to complete the chambers of the adjoining frames next to them. One of the said end plates is supported by a standard resting on the ground, and, by means of lugs cast on its sides, supports partly the two horizontal bars running longitudinally along the frames, which frames rest upon the said bars, by means of their above-mentioned arms or projections. The bars pass through corresponding lugs on the sides of the front end plate, to a second standard or support, where the two bars are joined together by means of a cross-beam extending across the end plate. A similar cross-beam joins together the said bars behind the back end plate. Between the front end plate and the cross-beam and front support, is a movable block, which a screw in the front support may be made to press against the front end plate, and thus firmly tighten together all the frames between the two end plates. On slightly loosening the said screw, the intermediate block falls and releases the frames, which may readily be separated as required.

The frames may be made to join tightly by means of India-rubber rings inserted round the rims in conical grooves, or by forming on the rims deep cylindrical grooves, or in any other convenient manner.

The frames having been properly tightened together, the semi-liquid substance to be operated upon is forced into the apparatus, passing through the channel in the rims of the frames, and entering the spaces enclosed

between the said frames. The liquid parts pass through the cloth or filtering-medium to between the gratings of the frames, whence they flow off through suitable channels or pipes cast under the said gratings, and the solid parts of the said semi-liquid accumulate outside the cloths, and form cakes, which, when the frames are separated, fall to the ground, and may be removed.

The under channels for the outlet of the liquid may be provided with stop-cocks, to stop off the flow of liquid from any compartment, when from any cause the liquid ceases to be clear.

Having thus explained the nature of our said invention, we will proceed to describe, with reference to the accompanying drawings, the manner in which the same is to be performed.

Figure I of the accompanying drawings represents a side elevation of a filtering-press constructed according to our invention.

Figure II is an end elevation of the same, and

Figure III a plan of the same.

Figure IV is a front view of one of the grated rings or circular frames, which, when secured together face to face, form the filtering-chambers, and

Figure V is a transverse section of Fig. IV.

Similar letters of reference refer to like parts in all these figures.

$A^1 A^2$ are two strong metallic circular plates, closing the ends of a series of grated rings or circular frames, $B B$, which, by means of side lugs or projections, $b b$, rest upon the side bars $C C'$. The said side bars $C C'$ pass through projections $a^1 a^2$ on the plates $A^1 A^2$, and are secured at one end to the cross-bar D , and at the other end to the cross-bar D' , the said cross-bar D' being carried by the standard E , and the cross-bar D being supported by the bars $C C'$ passing through the projections a^1 of the plate A^1 , which said plate A^1 is carried by the standard a .

The cross-bar D is provided with a powerful screw, d , actuated by a lever, D' , which said screw, d , may be made to press against the movable block D'' , which is capable of motion on its axis, D'' , so that when brought into the position indicated in the drawing, it fills up the space between the plate A^2 and screw d , and the action of the said screw d presses the said plates A^2 against the circular frames $B B$, and secures the series tightly together.

The frames $B B$, forming the filtering-chambers, are shown separately at Figs. IV and V. They consist each of a circular rim or ring, B , the central portion of which is provided with a grating of bars, $B^1 B^1$, cast with the rim B , or attached thereto. The said bars $B^1 B^1$ are less wide than the rim B , so that when a certain number of the said rings or circular frames B , with their gratings B^1 , are secured together face to face, they form two series of chambers, the one series composed of the gratings B^1 , the second of the spaces $B^2 B^2$.

Through the upper part of each rim B is an aperture or channel, I^1 , which channels, when the circular frames are secured together face to face, communicate one with the other throughout the entire length of the machine, and also with the spaces $B^2 B^2$ within and between the said frames. The continuous channel formed by the said apertures I^1 communicates externally, by means of a cock, H , and pipe T , with the "monte-jus," or juice-elevator, or other machinery used for forcing in the semi-liquid substance.

The inner surfaces of each of the metallic end plates $A^1 A^2$ are formed with a grating of bars similar to the bars B^1 , but closed exteriorly so as to complete the chambers of the adjoining frames B . On each side of the grating of bars B^1 , of the circular frames B , and over the bars of the end plates $A^1 A^2$, is attached a perforated metal plate, and over the said perforated plate are one or more woollen or hempen, cotton, or other suitable cloths, which may be secured in the following manner: $P P$, Fig. V, are metallic rings, which fit into circular recesses or grooves P^1 , Fig. IV, on each side of the frame B . The said grooves P^1 are sufficiently large to admit the ring with the cloth over it.

A circular piece of cloth, of rather larger diameter than the ring P , and surrounded by a hem containing a cord or string, the ends of which cord or string pass out of the hem, is spread over the ring P , and the ends of the string or cord being drawn tight and tied secure, the said cloth over the ring, the ring is then inserted into the groove P^1 , and secured in position by screws, the heads of which screws project on one side only, so that by turning the said screws half round, their projecting heads may be brought over the ring P , to fix it in position, or may be moved from off the ring to release it.

Another mode of attaching the cloths over the metallic perforated plates according to our invention, is to take two cloths, of the diameter of the outside of the frame, B with a hole made in each of the said cloths, corresponding in shape and position with the apertures I^1 , the said cloths being connected together by a hempen or other tube, in length equal to the thickness of the rim B , and sewn round the said holes. One of the said cloths is passed through the aperture I^1 , and both cloths are then spread, one over each face of the frame, and may be tied over the rim by strings attached to each cloth. In this case, as the cloths cover the parts where the rims join, it is preferred to insert in the said rims India-rubber rings covered with cloth, to preserve the said cloths, but other well-known appliances may be used for preventing the cloths from becoming injured at the parts where the frames join. It will be seen that each frame B requires two cloths, or a double cloth, and each end plate $A^1 A^2$ one cloth. In some cases wire gauze may be substituted for other cloths.

N are channels communicating with the spaces between the bars of the frames $B B$ and plates $A^1 A^2$. They are closed behind by plugs, N^1 , which may easily be removed to enable the channels N to be cleaned, and in front the channels N may be provided with cocks or taps $G G^1$.

M is a cock, communicating with the channel I^1 . The cock M is provided with a movable plug, M^1 , giving access to the channel I^1 . S is a cock, through which water may be introduced into the machine. R is the bed-plate on which the machine rests.

The working of our improved filtering-press is as follows: The cloths over the face of each frame having

been properly spread and secured, as above described, the frames B B are placed upon the bars C C', and between the end plates A¹ A². The block D³ is now raised to occupy the space between the end plate A² and the screw d, and the said screw d is screwed up by means of its lever D², and tightly presses and secures together the series of frames B B, and plates A¹ A². The cock H is now gently opened, and the semi-liquid substance to be operated upon is forced into the press, passing through the channels I¹ to the chambers or spaces B², between the frames. The liquid parts pass through the cloths to between the bars B¹, whence they flow out through the channels N and cocks G and G¹, and may be collected in a vessel, O. Should the spaces between the bars be full, the liquid would flow along a groove round the frame to the bottom and channel N. The solid parts of the said semi-liquid substances are arrested by the cloths, and form cakes in the chambers between the frames. When the liquid parts cease to flow, in consequence of the cakes becoming too hard, the cock H may be closed, and water introduced through the cock S, in order to carry off the remaining liquid. By opening the cock M, the liquid filling the channels I¹ may be driven out by steam.

The filtering operation being ended, the screw d is loosened, the intermediate block D³ falls, and the different frames and plates may be separated, one from the other, when the cakes will fall down under the machine, and may be removed.

Having thus described the nature of our said invention, and the means of carrying the same into effect, we wish it to be understood that we do not confine ourselves to the precise details herein described, and illustrated in the accompanying drawings, as the same may be varied without departing from the nature of our invention.

We claim—

1. The construction and arrangement of the grated circular frames and end plates, and the mode of introducing the semi-liquid substance to the filtering-chambers, through apertures made in the rims of each frame, the said apertures forming a continuous channel throughout the length of the press, in communication with each filtering-chamber, substantially as described and represented.
2. In combination with the removable frames B and movable head A², we claim the pivoted block D³ and central screw d, all constructed and arranged to operate in the manner and for the purpose substantially as herein set forth.
3. The arrangement of cocks H M, the latter having removable plug M', at the opposite ends of the channel formed by the spaces I¹ in the frames B, as herein shown and described, for the purpose specified.
4. The provision of each frame B with a channel, N, having a cock, G G¹, at its outer end, and a movable plug, N', at its opposite extremity, substantially as described.
5. We claim the side supports C C' and cross-bars D D', arranged as described, with relation to the stationary end piece A¹, movable piece A², and removable circular gratings B, substantially as represented.

EDOUARD ROETTGER,
P. DU RIEUX.
